UNITED STATES PATENT OFFICE.

ELMER JARED BLISS, OF EDGARTOWN, MASSACHUSETTS, ASSIGNOR TO REGAL SHOE COMPANY, OF BOSTON, MASSACHUSETTS, A CORPORATION OF MAINE.

DESIGN FOR A STREET-SIGN.

No. 39,465.

Specification for Design.

Patented Aug. 25, 1908.

Application filed April 4, 1903. Serial No. 425,281. Term of patent 14 years.

To all whom it may concern:

Be it known that I, ELMER JARED BLISS, a citizen of the United States, residing at Edgartown, in the county of Dukes and State of Massachusetts, have invented a new, original, and ornamental Design for a Street-Sign, of which the following is a specification, reference being had to the accompanying drawing, forming part thereof.

The figure is a side elevation of a street sign, showing my new design.

I claim:

The ornamental design for a street sign, as shown.

ELMER JARED BLISS.
